Frances Obrecht INVENTOR.

UNITED STATES PATENT OFFICE.

FRANCES OBRECHT, OF FLINT, MICHIGAN.

DESIGN FOR A SAMMY SANDMAN DOLL.

55,076.

Specification for Design.

Patented May 4, 1920.

Application filed November 8, 1919. Serial No. 336,766. Term of patent 7 years.

To all whom it may concern:

Be it known that I, FRANCES OBRECHT, a citizen of the United States, residing at Flint, in the county of Genesee and State of Michigan, have invented a new, original, and ornamental Design for a Sammy Sandman Doll, of which the following is a specification, reference being had to the accompanying drawing, forming part thereof.

The figure is a plan view of a "Sammy Sandman doll" showing my new design.

I claim:

The ornamental design for a "Sammy Sandman doll," as shown.

FRANCES OBRECHT.
